UNITED STATES PATENT OFFICE.

HARRY W. SMITH, OF GRAFTON, MASSACHUSETTS.

WEFT-REPLENISHING MECHANISM FOR LOOMS.

SPECIFICATION forming part of Letters Patent No. 692,935, dated February 11, 1902.

Application filed October 22, 1900. Serial No. 33,800. (No model.)

To all whom it may concern:

Be it known that I, HARRY W. SMITH, a citizen of the United States, residing at Grafton, county of Worcester, State of Massachusetts, have invented an Improvement in Weft-Replenishing Mechanism for Looms, of which the following description, in connection with the accompanying drawings, is a specification, like characters of the drawings representing

like parts.

The invention to be hereinafter described relates to that class of looms wherein filling-changing mechanism is employed to effect a supply of fresh filling without stopping the loom when that in an active shuttle has become practically exhausted, and more particularly to such type of loom employing shifting or changing shuttle-boxes.

It has heretofore been proposed to provide a drop or shifting shuttle-box loom with a filling changing or replenishing mechanism; but in such case the filling-changing mechanism has been operative to supply fresh filling only when the filling in an active shuttle has become broken or exhausted, whereas in my present invention I have devised a detecting mechanism which will indicate approaching exhaustion of the filling and prior to its complete exhaustion and while the shuttle still contains sufficient filling to make one or more picks will cause the filling-changing mechanism to become operative to effect a change of filling.

In adapting my invention to a shifting or changing shuttle-box loom, or one using different characters or colors of filling, it has been found preferable to locate the filling-changing mechanism at one side of the loom, and the feeler mechanism, which feels for and detects the condition of practical exhaustion of the filling, at the opposite side thereof in order to obviate the sudden and quick action of the former that would otherwise be necessary, and for practical embodiment of my invention I have shown and described herein a type of loom having a single shuttle-box at one side and changing or shifting boxes at the opposite side. In such type of loom it is desirable that the filling-changing mechanism shall be located at the side of the loom adjacent the single shuttle-box, such disposition of parts readily permitting the

change of filling as in the single-box loom or one using only one character or color of filling. I have therefore placed the detector mechanism on the side of the loom adjacent the shifting shuttle-boxes and so disposed the parts as that the feeler may enter and feel for the filling in that shuttle which is next to be put in play. As the shifting shuttle-boxes move up and down under the call of the pattern different shuttles will be moved onto the line of the race, and as it is only necessary to feel for and detect the condition of the filling in the shuttle that is about to be put in play I have devised a detecting mechanism which as the lay beats up will feel for the filling in the shuttle that is brought onto the line of the race, and should the filling be practically exhausted the detecting mechanism will indicate that fact and start other devices into operation to cause the filling-changing mechanism to operate to effect a change of filling by ejecting the practically exhausted filling and substituting a fresh supply when the indicating-shuttle has arrived at the filling-changing side of the loom.

In the drawings, Figure 1 is a front elevation, parts being broken away, of so much of a loom as is necessary to show the adaptation of my invention thereto. Fig. 2 is a side elevation of the same. Fig. 3 is a detached detail showing the feeler and some of its co-operating parts to be described. Fig. 4 is a detail in plan view of the feeler. Fig. 5 is a plan view showing the feeler as it appears when in contact with a filled carrier and as the lay beats up. Fig. 6 is a like view showing the feeler under like conditions when in contact with a practically-exhausted carrier.

The loom-frame A, crank-shaft C, lay H, pitman H', connecting the lay and crank-shaft, the cam-shaft B, the gears C' C², connecting the crank and cam shafts, and the main shuttle-box lever E, pivoted at E' on a bracket E' and connected to the shuttle-box rod n by the link n', said main shuttle-box lever receiving motion to raise and lower the shuttle-boxes, as desired, under the call of suitable pattern mechanism, are and may be as usual in looms containing drop or shifting shuttle-boxes, and such mechanism being common and well known by those skilled in the art need not herein be further elucidated.

Mounted on the loom-frame at the end thereof adjacent the single shuttle-box H^2 is any usual form or construction of filling feeder or hopper G^6 , containing a series of filling-carriers 22, arranged in groups, each group containing filling-carriers having different filling thereon corresponding with the filling used in the series of shuttles of the drop or shifting shuttle-boxes, and the feeder or hopper is moved positively and in unison with each change of position of the shuttle-boxes to thus place and keep opposite the transerrer 26 a filling-carrier having a filling corresponding in character or color with the filling in the then active shuttle.

In case of practical exhaustion of filling in the active shuttle, so that the filling-carrier has to be changed by substituting for the one then in the shuttle another having a fresh supply of filling, the feeder or hopper after the change of filling has been effected is given automatically a movement sufficient to bring into position a new group of filling-carriers, so as to place opposite the transerrer a filling-carrier in the new group which contains a filling corresponding with the filling just removed from the feeder or hopper and put into the shuttle. The filling feeder or hopper has then imparted to it differential movements and is oscillated and rotated in unison with the movements of the drop or shifting shuttle-boxes as necessity requires to always maintain a proper character or color of filling in position to be transferred to its proper shuttle, all as fully set forth in Letters Patent granted to Wyman and Crompton, No. 600,053, March 1, 1898, to which reference may be had. The shaft G' , carried by the brackets G and receiving motion from the main shuttle-box lever E through the link G^2 and rod G^4 , and the other adjunctive parts by which the described movements are given the feed-hopper through certain gears, only gears 31 32⁺ thereof being diagrammatically shown, are and may be all as fully described in said Patent No. 600,053, and these specific devices, forming no part of my present invention and being well understood by those skilled in the art, need not be herein further described.

In the present embodiment of my invention I have shown a drop or shifting shuttle-box D , having two cells; but it is to be understood, of course, that any number of cells may be employed, depending upon the pattern being woven, and this shuttle-box is mounted, as usual, on the shuttle-box rod n , the latter serving to raise and lower the boxes under the call of the pattern of the shuttle-box motion of any usual form and construction, so timed with reference to the movements of the lay that the cell which contains the shuttle to be next put in action will be brought to the line of the race as the lay beats up, as will hereinafter more fully appear. The shuttle-boxes rise and fall in suitable guides d on the guide-stand D' , preferably secured to one end of the lay, Fig. 1, as usual.

Suitably pivoted to the breast-beam at 47 is the transerrer 26, having its end a disposed with relation to the filling-carriers 22, 70 as shown in Patent No. 600,053 referred to, a spring a' normally holding the end of the transerrer above the lower carrier. Fixedly connected to the transerrer 26 at its pivoted connection 47 with the breast-beam is a depending arm a^2 , having pivoted at its lower end a^3 a dagger a^4 , the end of which is normally sustained out of the path of a bunter a^5 , carried by the lay. With a shuttle of usual construction as used in a filling-changing loom and as shown in Patent No. 600,053 in the single-box side of the loom adjacent the filling-changing mechanism it will be evident that if the end of dagger a^4 is put into the path of the bunter a^5 the transerrer will 85 be actuated on the beat-up of the lay to transfer a filling-carrier from the hopper or feeder to the shuttle and will at the same time eject the carrier then in the shuttle.

Each cell d' of the drop or shifting shuttle-box D is provided with a binder d^2 , pivoted at d^3 and normally pressed inward by a binder-spring d^4 . In the length of each binder d^2 there is provided an enlargement d^5 , having a perforation d^6 , through which the detecting device, to be hereinafter described, is adapted to project and feel for the filling on the carrier, the said perforation being located at a point in the binder opposite a portion of the base of the filling-carrier when the shuttle is in position in its cell.

Extending across the loom-frame below the breast-beam is a shaft b , having on the end thereof opposite the single shuttle-box a supporting-arm b' , provided with an enlarged or oval head b^2 , on which the dagger a^4 normally rests, the said dagger at the point of support on said head being also provided with a cam portion b^3 for the purpose of rocking the shaft b when the dagger is moved backward under 110 the action of the bunter to thereby reset the detecting mechanism, as will hereinafter appear.

Mounted on a bracket F , Fig. 3, secured to the loom-frame by bolt F' , is the detecting mechanism, comprising two feeler-fingers e' , loosely carried, so as to have sliding movement endwise in a case e^2 , secured to the bracket F , a spring e^3 being interposed between a collar e^4 on each finger and the case e^2 to normally hold said fingers in their projected position, as shown in Figs. 3 and 4, a stop e^5 on each finger serving to limit the outward or projecting movement of the fingers. Likewise supported on a bracket F^X , Figs. 1 and 3, as by bolts F^2 , is a guide or casing f , in which slides a drop-finger f' , normally under the depressing tension of a spring f^2 , one end of which is connected to the guide f at f^3 and the other to a pin f^4 , projecting from the drop-finger. The drop-finger is formed of two parts, the upper portion being hinged to the lower portion by a knife-joint f^5 and normally held open and in position shown by

Fig. 3 by a spring f^6 . At the end of the upper portion the drop-finger is enlarged and provided with a head f^7 , having a perforation f^8 , with which the feeler-finger e is adapted to be engaged under normal working conditions of the loom, the other feeler-finger e' bearing by its end against the solid portion of the head f^7 .

Secured to the end of shaft b below the feeler-fingers $e e'$ is an arm f^9 , having its end f^{10} in position below the guide f , so that when the drop-finger f^7 falls, as will be explained, the same contacts with the end of arm f^9 , and by virtue of its weight or the spring f^2 , or both, causes the shaft b to be turned to lift the dagger by means of the supporting-arm b' into the path of the bunter a^5 and effect a change of filling, as has been described.

The feeler-fingers $e e'$ are so positioned with relation to the shifting shuttle-boxes that as the lay beats up and the shuttle-box containing the shuttle next to be put in play approaches the forward position the feeler-fingers will enter the cell then substantially on a line with the race, and if the filling f^{11} on the carrier f^{12} contained in that shuttle is full or in sufficient working quantity both of the fingers $e e'$ will be pushed back together by the filling on the carrier, as indicated in Fig. 5, and the upper portion of the drop-finger will remain in engagement with the feeler-finger e , the said upper portion of the drop-finger merely yielding on its pivot against the tension of spring f^6 ; but should the filling be practically exhausted, as shown in Fig. 6, then the feeler e' will contact with the base f^{13} of the carrier f^{12} and be pushed backward on the continued forward movement of the lay. There being no practical amount of filling of the carrier f^{12} , the finger e will not be pushed back to the same extent as finger e' , and the head f^7 of the drop-finger will by the finger e' be pushed off the end of finger e , thus permitting the drop-finger to fall under the action of gravity or spring f , or both, and, striking the arm f^9 , turn the shaft, so that the supporting-arm b' is raised to carry the end of the dagger in position to be struck by the bunter a^5 , and thus cause a transfer of filling on the next beat-up when the indicating-shuttle is in the single shuttle-box adjacent the filling-changing mechanism. As the lay thus moves forward the cam b^3 on the dagger depresses the end b^2 of the supporting-arm, thereby raising the end f^{10} of the arm f^9 and lifting the drop-finger against the action of its spring, and the feeler-fingers $e e'$ being now held in projected position by the springs e^3 the rounded end f^{14} of the upper portion of the drop-finger is carried upward until the end of feeler-finger e again engages the perforation f^8 in the head f^7 of the drop-finger, and the parts thus resume their original position, as will be fully understood.

Thus it will be seen that the detecting mechanism is held stationary on a part of the loom-

frame or the bracket secured thereto in such position with respect to the shifting shuttle-boxes as that when the lay beats forward the feeler-fingers will enter the perforation in the binders and feel for the filling in the shuttle and this action will take place on every beat-up of the lay; but so long as the filling in the shuttle is of sufficient quantity for working purposes both feeler-fingers will be pushed to the rear by the onward movement of the lay, and the feeler-finger e will continue to sustain the drop-finger f^7 . Should, however, the filling be nearly exhausted, the feeler-fingers in their rearward movement will be unequally moved as the lay beats up and the feeler-finger e' will force head f^7 of the drop-finger from supporting contact with the finger e , and the operation of changing the filling, as above set forth, will on the next beat-up of the lay when the depleted shuttle or carrier has reached the single-box side of the loom adjacent the filling-changing mechanism take place. In other words, the detecting mechanism through the feeler-fingers feels for the filling on each beat-up of the lay, and when they have detected the practical exhaustion of filling they will trip the drop-finger, so that on the next beat-up of the lay the depleted shuttle then being in the single box the filling-changing mechanism will operate to change the filling.

While I have shown as the present embodiment of my invention devices for changing the filling-carrier in the shuttle, it is to be understood that the invention is not necessarily limited thereto, but that, if desired, the shuttles themselves may be changed, as will be well understood by those skilled in the art. Moreover, while I have shown only two cells in the shifting shuttle-boxes, it is to be understood that any number of cells may be employed as desired, the essence of the invention being the provision of detecting mechanism held on the loom-frame adjacent the shifting shuttle-boxes, which shall enter the cell of the shuttle-boxes then on the line of the race to detect the condition of the filling in the shuttle and to effect a change of filling on the next beat-up should the filling in the said shuttle be practically exhausted.

The details of my invention may of course be varied, and I do not regard the specific embodiment of the invention herein described as being essential.

The shifting movement of the shuttle-boxes and the position of the feeler-fingers $e e'$ are so related to each other that as the lay approaches its forward position the feeler-fingers may enter the shuttle and feel for the filling without interference with the shifting movement of the shuttle-boxes, as will be clear to one skilled in the art.

Having thus described my invention, what I claim, and desire to secure by Letters Patent, is—

1. In a loom the following instrumentalities, viz: a lay, shifting shuttle-boxes, detecting mechanism adjacent the shifting shut-

- tle-boxes adapted to feel for the filling in one of the shuttles as the lay beats up, and filling-changing mechanism operative on the practical exhaustion of the filling in an active shuttle to supply fresh filling.
2. In a loom the following instrumentalities, viz: a lay, shifting shuttle-boxes, a filling-changing mechanism, a detecting mechanism having provisions for entering and feeling for the filling in the shuttles and means for causing the operation of the filling-changing mechanism to effect a change of filling when that in an active shuttle has become practically exhausted.
- 15 3. In a loom the following instrumentalities, viz: a lay, shifting shuttle-boxes, a filling-changing mechanism, a stationary detecting mechanism adjacent the shifting shuttle-boxes having provisions for feeling for the filling in one of the shuttles and means for causing the operation of the filling-changing mechanism to effect a change of filling when that in the active shuttle has become practically exhausted.
- 25 4. In a loom the following instrumentalities, viz: a lay, shifting shuttle-boxes, a filling-changing mechanism, a stationary detecting mechanism comprising fingers adapted to enter a cell of the shifting shuttle-box to feel for the filling in the shuttle, and means to cause the filling-changing mechanism to operate to supply fresh filling when that in an active shuttle has become practically exhausted.
- 35 5. In a loom the following instrumentalities, viz: a lay, shifting shuttle-boxes at one end thereof, a filling-changing mechanism at the opposite end thereof, a detecting mechanism adjacent the shifting shuttle-boxes having provision for feeling for the filling in one of the shuttles as the lay beats up, and means for causing the operation of the filling-changing mechanism to effect a change of filling when that in an active shuttle has become practically exhausted.
- 45 6. In a loom the following instrumentalities, viz: a lay, shifting shuttle-boxes at one end thereof, a filling-changing mechanism at the opposite end thereof, a stationary detecting mechanism provided with feeler-fingers to enter a cell of the shifting shuttle-boxes and means under the control of said feeler-fingers to cause the operation of the filling-changing mechanism when the filling in an active shuttle has become practically exhausted.
- 55 7. In a loom the following instrumentalities, viz: a lay, shifting shuttle-boxes at one end thereof, each cell of which is provided with a binder having a perforation therein, a filling-changing mechanism at the opposite end of the lay, a detecting mechanism having feeler-fingers adapted to enter each cell of the shuttle-boxes, and means under control of the feeler-fingers for causing the filling-changing mechanism to become operative to effect a change of filling when that in an active shuttle has become practically exhausted.
8. In a loom the following instrumentalities, viz: a lay, shifting shuttle-boxes the cells of which are provided with perforations for the reception of feeler-fingers, a detecting mechanism mounted on the loom-frame comprising a pair of feeler-fingers located adjacent the shifting shuttle-boxes, a filling-changing mechanism and means controlled by said fingers for causing the filling-changing mechanism to effect a change of filling when that in an active shuttle has become practically exhausted.
- 90 9. In a loom the following instrumentalities, viz: a lay, shifting shuttle-boxes at one end thereof, a filling-changing mechanism, a detecting mechanism supported by the loom-frame adjacent the shifting shuttle-boxes and comprising yielding fingers adapted to enter a cell of the shifting shuttle-boxes to feel for the filling in the shuttle, and means under control of said fingers for causing the filling-changing mechanism to supply fresh filling when that in an active shuttle has become practically exhausted.
- 95 10. In a loom the following instrumentalities, viz: a lay, shifting shuttle-boxes at one end thereof, a filling-changing mechanism, a detecting mechanism supported by the loom-frame adjacent the shifting shuttle-boxes and comprising yielding fingers adapted to enter a cell of the shifting shuttle-boxes to feel for the filling in the shuttle, a drop-finger under control of the feeler-fingers, a dagger and means between the drop-finger and dagger to position the latter to cause the operation of the filling-changing mechanism when the filling in an active shuttle has become practically exhausted.
- 100 11. In a loom the combination of the lay, shifting shuttle-boxes at one end thereof, a filling-changing mechanism, yielding feeler-fingers supported adjacent the shifting shuttle-boxes and adapted to enter a cell of said boxes to feel for the filling in the shuttle, a dagger and means interposed between the dagger and feeler-fingers to position the former to cause the filling-changing mechanism to operate when the filling in an active shuttle has become practically exhausted.
- 110 12. In a loom the combination of the lay, shifting shuttle-boxes, a detecting mechanism including feeler-fingers adapted to enter a shell of the shuttle-boxes to feel for the filling in the shuttle next to be put in play, a drop-finger normally sustained by one of said feeler-fingers and adapted to be disengaged therefrom by the other feeler-finger when the filling in said shuttle has become practically exhausted, and filling-changing mechanism made operative by the drop-finger to effect a change of filling when that in said shuttle has become practically exhausted.
- 120 13. In a loom the following instrumentalities: a filling-changing mechanism, a lay, a detecting mechanism including two feeler-fingers adapted to enter the shuttle and feel for the filling, and mechanical means under

control of said feeler-fingers for operating the filling-changing mechanism to supply fresh filling when that in the shuttle has become nearly exhausted.

- 5 14. In a loom the following instrumentalities: a filling-changing mechanism, a lay, a detecting mechanism including two independently-movable feeler-fingers adapted to enter the shuttle and feel for the filling, and
- o mechanical means under control of said feeler-fingers for operating the filling-chang-

ing mechanism to supply fresh filling when that in the shuttle has become nearly exhausted.

In testimony whereof I have signed my 15 name to this specification in the presence of two subscribing witnesses.

HARRY W. SMITH.
